George Percy Parker, Chelmsford, England, as-
signors to Radio Corporation of America, a cor-
poration of Delaware

Application April 26, 1941, Serial No. 390,484
In Great Britain March 27, 1940

4 Claims. (Cl. 250—17)

The present invention relates to radio trans-
mitters and particularly to radio transmitters
for aircraft. It is not, however, so limited.

The principal object of the invention is to
enable the maximum voltage, over the frequency
range of a radio transmitter, to be maintained
without requiring the services of a skilled opera-
tor.

In certain radio transmitters, particularly in
certain radio transmitters for aircraft, the maxi-
mum power that can be applied to the aerial is
limited by the maximum voltage that the vari-
ous aerial insulators will withstand. This maxi-
mum voltage will be obtained for a given aerial
from a given amount of aerial power at the mini-
mum tuning frequency, where the aerial impedance
is at a maximum. If the amount of power
that can be applied to the aerial be limited to the
power which will give the maximum voltage at
the minimum frequency, it follows that at higher
frequencies the aerial will be operating at volt-
ages which are much less than the permissible
maximum voltage. To obtain a constant maxi-
mum voltage over a tuning range will require
that the power delivered to the aerial shall be in-
creased as the frequency is increased, an opera-
tion which would normally require the services of
a skilled operator.

According to the invention, a radio transmitter
having a final amplifier stage includes in the an-
ode circuit of said stage a current indicator
means for indicating the optimum anode supply
and means, gang controlled with the tuning re-
actance, for shunting a variable portion of the
anode current around said indicator means,
whereby said indicator means provides a sub-
stantially fixed indication of the optimum anode
supply irrespective of the frequency to which the
transmitter is tuned.

The means for varying the grading of said cur-
rent indicator may comprise a variable resistance
connected across the current indicator and the
resistance may be gang controlled with a variable
aerial tuning inductance.

An embodiment of the invention is illustrated
in the sole figure of the accompanying drawing
wherein PT indicates the final amplifier valve of
the transmitter, the anode of the valve being
connected to a source S of high positive potential
through a high frequency choke HFC in series
with a resistance R, milliammeter MA, and a
rheostat RH. Output is taken from valve PT
through a blocking condenser C and applied to
the aerial inductance AL, the point of application
being, if desired, adjustable as indicated in con-

ventional manner. The aerial A is connected to
a point on the aerial inductance and the lower
end of the inductance is earthed.

Shunted across the milliammeter and resist-
ance R is a variable resistance PR, the tapping
point p' of which may be adjusted in conven-
tional manner. The amount of aerial tuning
inductance can be selected by a connector p''.
This connector is adapted to short circuit a
requisite number of turns of the aerial tuning in-
ductance for the desired frequency at which the
transmitter is to operate. The tap p' and con-
nector p'' are gang controlled as indicated at G.

On the scale of the milliammeter a loading
mark is provided and the operator is required to
adjust the anode feed to this mark.

As the frequency of operation is reduced (or
increased) more (or less) aerial tuning induct-
ance will be required and the adjustment of the
aerial tuning inductance p'' will, owing to the
gang control, be accompanied by an increase (or
decrease) in the amount of resistance shunting
the milliammeter. Thus, the more inductance
that is included in the aerial circuit, the higher
will be the value of the resistance shunting the
milliammeter, and consequently, since the feed
will be adjusted to a given mark on the scale of
the instrument, the true anode feed will be re-
duced.

The value of the milliammeter shunt resistance
is so chosen that the aerial voltage will remain
approximately constant over the frequency range
of the transmitter, while the value of the current
shown on the anode feed milliammeter remains
constant.

In the figure the maximum aerial tuning in-
ductance is represented as included, and conse-
quently the maximum amount of resistance is
indicated as shunted across the milliammeter.

We claim:

1. In a radio transmitter circuit arrangement,
a tuning device for the output circuit of a dis-
charge tube in a power output stage, an ammeter
and a resistor in said output circuit, a rheostat
in shunt with said ammeter and resistor, means
for adjusting the anode current in said tube to
an optimum value for any desired adjustment of
said tuning device, and means providing gang
control of said tuning device and said rheostat,
said rheostat being operable to produce a sub-
stantially fixed ammeter reading for all adjust-
ments of said tuning device.

2. The combination according to claim 1 and
including an inductance coil in said tuning de-
vice, said coil having a connection at one end to

an adjustable tap for short-circuiting a desired number of convolutions of said coil, said tap being adjustable by said gang control means.

3. A transmitting amplifier system comprising a final stage including the anode circuit of a discharge tube, means including a current-responsive instrument in said anode circuit for indicating the optimum anode current, a tuning reactance coupled to said anode circuit, and gang-controlled means for simultaneously adjusting the sensitivity of said instrument and the tuning of said reactance, whereby the indication on said instrument of optimum anode current for different operating frequencies of said reactance is maintained substantially constant.

4. In the art of adjusting the final amplifier stage of a radio transmitter, where said stage in-

cludes the anode circuit of a discharge tube, a resistor and an ammeter in the anode circuit, a potentiometer in shunt with said resistor and ammeter, and a tuning reactance coupled to said anode circuit, said potentiometer and tuning reactance being gang controlled, the method of adjusting the anode current to an optimum value for a given frequency to which said reactance is tuned which comprises varying the amount of anode current bypassed through said potentiometer as a function of the frequency to which said reactance is tuned, and causing said ammeter to make substantially the same indication for all adjustments of said tuning reactance.
